CLAIM

The ornamental design for figure attached through window, as shown and described.

DESCRIPTION

FIG. 1 is a front and exploded, perspective view of a figure attached through window, formed of 2 pieces, which when secured to the opposed faces of a window pane, visually seem like a creature is smashing through a pane of glass of a window, here in the form of a slimy faced character, according to the present design;

FIG. 2 is a bottom plan view thereof;

FIG. 3 is a top plan view thereof;

FIG. 4 is a left side elevation view thereof;

FIG. 5 is a right side elevation view thereof;

FIG. 6 is a front view thereof; and,

FIG. 7 is a rear view thereof.

The dotted lines in FIGS. 2-5 are for environmental purposes only. They represent a pane of glass to which the two sections of the present invention will be secured, when in use. The pane of glass forms no part of the present invention.
